CLAIM

The ornamental design for an “angle cutter,” as shown and described.

DESCRIPTION

FIG. 1 is a perspective view of angle cutter showing my new design;

FIG. 2 is a front elevational view thereof;

FIG. 3 is a back elevational view thereof;

FIG. 4 is a left side elevational view thereof;

FIG. 5 is a right side elevational view thereof;

FIG. 6 is a top view thereof;

FIG. 7 is a bottom view thereof; and,

FIG. 8 is a reference view thereof.

The broken lines shown in the figures are for illustrative purposes only and do not form part of the claimed design.
